UNITED STATES PATENT OFFICE.

LORING D. SHAW, OF BOSTON, MASSACHUSETTS.

IMPROVEMENT IN AUTOMATIC RELIEF-VALVES.

Specification forming part of Letters Patent No. 159,045, dated January 26, 1875; application filed August 10, 1874.

To all whom it may concern:

Be it known that I, LORING D. SHAW, of Boston, in the county of Suffolk and State of Massachusetts, have invented certain new and useful Improvements in Automatic Relief-Valves; and do hereby declare that the following is a full, clear, and exact description thereof, which will enable others skilled in the art to which it pertains to make and use the same, reference being had to the accompanying drawings, and to the letters of reference marked thereon, which form a part of this specification.

My invention relates to improvements in automatic relief apparatus for the purpose of preventing the bursting of fire-engine hose if the pressure is suddenly increased therein, as is constantly the case if the valve or cut-off at the nozzle is closed before the pump is stopped from working. This, my invention, is also very useful for other purposes besides the above named.

My invention consists in the combination, with a cylinder in which two different size pistons attached to a piston-rod are movable, of a valve-cylinder provided with two entrances to the said cylinder; a double-acting valve that is forced onto its seat by a pair of adjustable spiral springs. A return-pipe leads from the aforesaid valve-cylinder to the suction-pipe of the pump, through which the liquid escapes from the upper part of the cylinder as soon as the pressure in the hose-pipe falls below the standard pressure at which the valve is regulated to open.

On the drawings, Figure 1 represents a ground plan of my invention. Fig. 2 represents a side elevation. Fig. 3 represents an end elevation. Fig. 4 represents a longitudinal section on the line A B, shown in Fig. 1, and Fig. 5 represents a longitudinal section on the line C D, also shown in Fig. 1.

Similar letters refer to similar parts wherever they occur on the drawings.

a represents the cylinder, the lower part, a', of which is reduced in diameter, as shown in Figs. 4 and 5. A piston, b, is movable in the cylinder a, and provided with a piston-rod, c, by means of which the piston b is connected to a secondary smaller piston, d, that is movable in the smaller cylinder a'. From the cyl-

inder a, and at a place between the pistons b and d, leads a pipe, e, to the pipe chamber or nozzle, in which the pressure is to be automatically regulated. This said pipe e may be connected directly to the delivery-pipe of the pump, or at some suitable place between the delivery-pipe of the pump and the valve or cut-off on the nozzle of a fire-engine hose. From the smaller cylinder, a', leads a pipe or opening, f, to the suction-pipe of the pump, which opening is closed by the piston d when the latter is in its highest position. A valve-cylinder, g, is located in close proximity to the larger cylinder, a, and is provided with two openings, h and i, one below and the other above the piston b, by which communication is established between the pressure-pipe e, cylinder a, and valve-cylinder g. In the valve-cylinder g is the valve k, movable up and down in a vertical direction, and is held onto its seat in the valve-cylinder g by means of a pair of spiral springs, l l, cross-bars m n, and a regulating-screw, o, as shown in Fig. 3. The cross-bar n is provided with an index, p, by means of which and a graduated scale, q, the pressure on the valve k from the springs l l can be adjusted so that the said valve k will open at any desired pressure. The valve k is provided with two openings, viz., one, r, through which the liquid can flow from the cylinder a, opening h, and valve-cylinder g, through the opening i, into the space above the piston b, when the pressure in the hose exceeds that for which the valve k is regulated. As soon as the liquid is forced above the piston b it moves the said piston downward, and in so doing the piston d is forced by the opening f, thereby allowing the liquid in the force-pipe e to return through the cylinder a' and pipe f to the suction part of the pump, by which the extra pressure is reduced, and when the pressure is reduced to that of the springs l l the valve k is forced onto its seat, and the pistons b and d are forced upward by the pressure of the liquid from the pipe e. As the pistons b and d rise upward the suction-pipe f is closed by the lower piston, d, and the liquid above the piston b is forced out through the opening i, the diametrical opening s in the valve k, and the return-pipe t to the suction-pipe f. The suction in the pipe f tends to create a vacuum in the upper

part of the cylinder *a* above the piston *b*, by which the latter is drawn still more into its highest position.

From the above will be seen that my relief apparatus is working automatically in both directions, both closing and opening the return to the suction-pipe, by which the operator is relieved of all care.

What I wish to secure by Letters Patent and claim is—

The combination, with the cylinders *a a'* and their pistons *b d* and openings *e f*, of the valve-

cylinder *g*, its openings *h i*, and double-acting valve *k*, with its openings *r s*, and the return-pipe *t* to the suction-pipe, as and for the purpose set forth and described.

In testimony that I claim the foregoing as my own invention I have affixed my signature in presence of two witnesses.

LORING D. SHAW.
